UNITED STATES PATENT OFFICE.

VICTOR JEAN BAPTISTE GATTELET, OF LYON, FRANCE.

MEANS FOR ATTACHING THE MOP CLOTH TO THE HEAD OF A MOP.

Application filed October 14, 1922. Serial No. 594,483.

To all whom it may concern:

Be it known that I, VICTOR JEAN BAPTISTE GATTELET, a citizen of the French Republic, and resident of Lyon, France, have invented 5 certain new and useful Improvements in Means for Attaching the Mop Cloth to the Head of a Mop, of which the following is a specification.

This invention relates to a new or improved means for attaching the mop cloth to the head of a mop.

It consists in mounting the cloth on an elastic band having a number of eyelets arranged at intervals by which it can be attached to hooks arranged on the edge of the wooden head serving to carry the mop cloth.

The elasticity of the band can be obtained by employing either an elastic fabric or a band of rubber, or by one or more metallic 20 springs preferably arranged in the interior of the band.

The accompanying drawing show by way of example two applications of the invention.

25 Fig. 1 is a perspective view of a mop head provided with a cloth formed in accordance with the present invention.

Fig. 2 is a plan view of same.

Figs. 3 and 4 are respectively section and 30 plan view of a modification of this arrangement.

The band *a* of the mop cloth *b* is made of elastic fabric. It is provided at intervals with eyelets *c'*, *c²*, *c³*, by which it can be

attached to the hooks *d'*, *d²*, *d³*, arranged 35 around the edge of the head *e*.

This head may be of any shape and made entirely of wood as shown in Figs. 1 and 2 or of wood reinforced with a metal plate *f* as shown in Figs. 3 and 4.

40 The upper surface of the head is fitted with a bracket *g* between the sides of which a socket *h* is pivoted into which a handle *i* may be screwed to operate the mop.

The cloth is placed in position by passing 45 the eyelet *c'* over the hook *d'*, then pulling the elastic band *a* and passing the eyelet *c²* over the hook *d²* and so on until the last eyelet *c³* is affixed to the hook *d'*.

The small cloth *j*, placed under the head, 50 is attached in the same way between the two hooks *d'* and *d²*.

What I claim and desire to secure by Letters Patent is:

55 A mop comprising a head having hooks on its periphery the bills of which all extend in the same direction, and a mop cloth having an elastic band provided with eyes to receive the hooks, said cloth being stretched around the periphery of the head 60 and by its retraction causing the eyes to be held against the shanks of the hooks at the inner ends of the bills thereof.

In witness whereof I affix my signature.

VICTOR JEAN BAPTISTE GATTELET.
